UNITED STATES PATENT OFFICE.

CHARLES ORTEGA, OF SAN DIEGO, CALIFORNIA.

ROASTING MACHINE.

Application filed December 17, 1920. Serial No. 431,510.

To all whom it may concern:

Be it known that I, CHARLES ORTEGA, a citizen of the United States, residing at San Diego, in the county of San Diego and State of California, have invented a certain new and useful Roasting Machine, of which the following is a specification.

My invention relates to a machine for roasting the outer surface of pimientos, 10 chilis and like products to facilitate the removal of the peel and the objects of my invention are: First, to provide a machine in which large quantities of pimientos, chili or the like may be subjected to a heated surface and turned thereon, whereby the whole 15 surface of the article to be roasted will be subjected to a heated surface so that the peel may be readily removed; Second, to provide a machine of this class which is 20 automatic throughout; Third, to provide a machine of this class in which a large quantity of fruits may be passed and properly subjected to heat on their outer surface; Fourth, to provide means for revolving and 25 turning the article to be roasted on its outer surface; Fifth, to provide a novel revolving oven for roasting purposes; Sixth, to provide a novel means of revolving said oven; Seventh, to provide a novel supporting 30 means for the revolving ovens; Eighth, to provide a novel means for turning the fruit in said oven; Ninth, to provide a novel means for regulating the heat to said ovens and Tenth, to provide a machine of this 35 class which is very simple and economical of construction, durable, easy to operate, efficient in its action, and which will not readily deteriorate or get out of order.

With these and other objects in view as 40 will appear hereinafter my invention consists of certain novel features of construction, combination and arrangement of parts and portions as will be hereinafter described in detail and particularly set forth in the 45 appended claims, reference being had to the accompanying drawings and to the characters of reference thereon which form a part of this application in which:

Figure 1 is a front elevational view of a 50 fragmentary portion of a furnace with two of my roasting ovens positioned therein; Fig. 2 is a rear view thereof; Fig. 3 is a longitudinal sectional view through 3-3 of Fig. 1 and Fig. 4 is a sectional view through 55 4-4 of Fig. 3.

Similar characters of reference refer to

similar parts and portions throughout the several views of the drawings.

The furnace 1, tubular member 2, supporting members, 3, 4, 5 and 6, worm wheel 60 7, worm pinion 8, clutch member 9, clutch member 10, lever 11, support 12, chute 13 and conveyor 15 constitute the principal parts and portions of my roasting machine.

The furnace 1 is shaped as shown best in 65 Figs. 3 and 4, composed of fire brick and mounted longitudinally therein and positioned on an angle therein is the tube 2 shown best in Fig. 3 of the drawings. This tube 2 is of sufficient length so that it extends out of the furnace at opposite ends. It is provided in one end with a spiral member 2^a which is adapted to start the articles to be roasted in a circuitous and inward movement. Extending from this 70 portion 2^a is a bar 2^b secured to the inner side of the tube which is for the purpose of increasing the agitation of the mass of articles to be roasted. This tube is supported at the outlet end by means of a supporting member 3 which consists of a bifurcated flange member provided with a plurality of rollers 3^a upon which rests the end of the tube 2 and mounted on this supporting member 3 is a cap member 4 secured thereto by 75 means of bolts 4^a and it is also provided with a roller 4^b which is adapted to rest against the surface of the tube, thus providing roller means for facilitating the revolution of the tube in the furnace. It will be 80 noted that the member 3 may be a plate portion of the furnace, if desired, as shown best in Figs. 1 and 3 of the drawings. The opposite end of the tube 2 is supported by 85 means of a supporting member 5 which is positioned upon a supporting bracket 12 positioned against the back end of the furnace. This supporting member 5 is also a bifurcated flange member and provided with rollers 5^a. It will be noted, however, that 90 these rollers 5^a are flanged rollers and tube 2 is provided with an annular collar 2^c over which these rollers 5^a are mounted which holds the tube 2 from moving longitudinally as well as providing means for supporting it while it revolves. This member 5 is provided with a cap member 6 by means of bolts 6^a which is a hollow member provided with another flanged roller 6^b. Secured around this tube 2, at the extended 95 end at the rear of the furnace is a worm wheel 7 which meshes with a worm pinion 100 105 110

8 mounted on a shaft 8^a and also mounted on this shaft are clutch members 9 and 10, the clutch member 9 connecting with the pinion 8 and the clutch member 10 being shifted by means of a lever 11, thus providing means for shifting the pinion 8 into and out of gear with the shaft 8^a. This shaft 8^a is supported on journals 8^b which are also supported on the supporting bracket 12. 10 This shaft 8^a is operated by any driving mechanism. Extending into the end of the tube 2 at the upper intake end is a slanting chute 13 which is the feed chute for feeding the articles to be roasted. Below the 15 opposite end of the tube 2 is a conveyor 14 for conveying the articles away from the tube after they have been roasted.

It will be noted that the furnace structure is such that there is an exit from the 20 furnace approximately at the middle of the tube so that only approximately one-half of the tube is heated as there is no fire in the rear portion of the furnace, and that there is only a small space above and around the 25 sides of the tube 2, all as shown best in Figs. 3 and 4 of the drawings.

Though I have shown and described a particular construction, combination and arrangement of parts and portions I do not 30 wish to be limited to this particular construction, combination and arrangement but desire to include in the purview of my invention, the construction, combination and arrangement substantially as set forth in the 35 appended claims.

It is obvious that with this construction, 40 there is provided a roasting machine particularly adapted for roasting the outer surface of pimientos, chili and the like, to facilitate the removal of the peeling; that the tube 2 is heated properly and revolved in its heated condition by means of the worm wheel 7 and pinion 8 so that the articles to be roasted are continually turned with the 45 revolution of the tube and further agitated by means of the bar 2^b and fed inwardly and started properly by means of the spiral member 2^a at the inlet end; that the flanged rollers in connection with the annular band 50 2^c supports the tube 2 against longitudinal movement as well as facilitating its revolution; that the cap members 4 and 6 may be readily removed to facilitate the repairing of the machine to take up wear and to facilitate 55 its being assembled; that there may be as many of these roasting units as desired, placed side by side in a multiple furnace built for the purpose and operated simultaneously or one at the time as desired.

60 Having thus described my invention what I claim as new and desire to secure by Letters Patent is:

1. A roasting machine, including a revolvably mounted, horizontally inclined tube, 65 a furnace adapted to normally heat only one

end of said tube and slightly heat the other end in which said tube is revolvably mounted with its opposite ends extending therefrom.

2. A roasting machine, including a revolvably mounted, horizontally inclined tube, 70 a furnace adapted to normally heat only one end of said tube and slightly heat the other end in which said tube is revolvably mounted with its opposite ends extending therefrom and means for supporting said tube for revoluble movement at its opposite ends, including annular supporting members, rollers revolvably mounted in said annular supporting members and a band secured around said tube adapted to engage the side edges of said 75 rollers.

3. A roasting machine, including a revolvably mounted, horizontally inclined tube, a furnace adapted to normally heat only one end of said tube and slightly heat the other end in which said tube is revolvably mounted with its opposite ends extending therefrom and means for supporting said tube for revoluble movement at its opposite ends, including annular supporting members, rollers revolvably mounted in said annular supporting members and a band secured around said tube adapted to engage the side edges of said 80 rollers, a spiral member positioned in the one end of said tube extending only a short distance therein, and a longitudinal bar extending from said spiral member into said tube secured to one side thereof. 90

4. A roasting machine, including a revolvably mounted, horizontally inclined tube, a 100 furnace adapted to normally heat only one end of said tube and slightly heat the other end in which said tube is revolvably mounted with its opposite ends extending therefrom, means for supporting said tube for revoluble movement at its opposite ends, including annular supporting members, rollers revolvably mounted in said annular supporting members and a band secured around said tube adapted to engage the side edges of said 105 rollers, a spiral member positioned in the one end of said tube extending only a short distance therein, a longitudinal bar extending from said spiral member into said tube secured to one side thereof, and means for revolving said tube, including a worm wheel secured around one of the extended ends of said tube, a pinion meshing with said worm wheel and means for revolving said pinion. 110

5. A machine of the class described, including a furnace provided with a central vertical flue, a tubular member revolvably mounted longitudinally in said furnace with its opposite ends extending from said furnace so constructed that only one-half of 120 said tube is normally heated while the other half is only slightly heated, a plurality of plain rollers for supporting one of the extended ends of said tubular member, a plurality of flanged rollers engaging a band se- 125 130

cured to the opposite extended ends of said tubular member for supporting said tubular member against longitudinal movement, a spiral member positioned in the inner surface of the intake end of said tubular member, a longitudinal bar positioned on the inner surface of said tubular member extending from said spiral member inwardly.

6. A machine of the class described, including a furnace, a tubular member revolvably mounted longitudinally in said furnace with its opposite ends extending from said furnace, a plurality of plain rollers for supporting one of the extended ends of said tubular member, a band secured to the opposite extended end of said tubular member, a plurality of flanged rollers engaging said band for supporting said tubular member

against longitudinal movement, a spiral member positioned on the inner surface of the intake end of said tubular member, a longitudinal bar positioned on the inner surface of said tubular member extending from said spiral member inwardly and means for revolving said tubular member comprising a worm wheel secured on one extended end of said tubular member, a pinion meshing with said worm wheel, a clutch member in connection with said worm pinion and a shaft in connection with said clutch member.

In testimony whereof, I have hereunto set my hand at San Diego, California, this 6th day of December, 1920.

CHARLES ORTEGA.
